UNITED STATES PATENT OFFICE.

RALPH TYRRELL, OF CLEVELAND, OHIO.

DESIGN FOR RUBBER MATTING.

46,761.

Specification for Design.

Patented Dec. 8, 1914.

Application filed September 21, 1914. Serial No. 862,817. Term of patent 14 years.

To all whom it may concern:

Be it known that I, RALPH TYRRELL, a citizen of the United States, residing in the city of Cleveland, county of Cuyahoga, State of Ohio, have invented a new, original, and ornamental Design for Rubber Matting, of which the following is a specification, reference being had to the accompanying drawings, in which—

Figure 1 is a plan view; and Fig. 2 an

enlarged cross-sectional view of a piece of matting showing my design, taken on the line A of Fig. 1.

I claim:

The ornamental design for rubber matting as shown.

RALPH TYRRELL.
